COMPRESSOR SHAFT ASSEMBLY

Filed July 2, 1948

UNITED STATES PATENT OFFICE

2,588,126

COMPRESSOR SHAFT ASSEMBLY

Lowell M. Kurtz, Erie, Pa., assignor to General
Electric Company, a corporation of New York

Application July 2, 1948, Serial No. 36,720

13 Claims. (Cl. 308—163)

1

My invention relates to compressors for refrigerating machines and the like and more particularly to shaft assemblies for such compressors.

In the manufacture of such items as compressors in large quantities the size of the various parts may vary slightly within the range of tolerances. In hermetically sealed motor compressor units the crankshaft of the compressor is carried within a frame. Manufacturing tolerances with regard to the shaft and the frame, for example, may result in a variation between different compressors in the amount of the end play of the shaft relative to the frame. Such variations might result in an undesirably large amount of end play and in a resultant unsatisfactory operation of the compressor. Accordingly, it is an object of my invention to provide an improved arrangement for adjustment of the end play of a compressor shaft assembly.

Further objects and advantages of my invention will become apparent as the following description proceeds and the features of novelty which characterize my invention will be pointed out with particularity in the claims annexed to and forming part of this specification.

For a better understanding of my invention reference may be made to the accompanying drawing in which Fig. 1 is an elevation view, partly in section, of a motor-compressor unit embodying my invention; Fig. 2 is an exploded view of some of the elements included in Fig. 1; Fig. 3 is a sectional view of a portion of a compressor assembly illustrating a modified form of my invention; Fig. 4 is an exploded view of some of the elements included in Fig. 3; Fig. 5 is a sectional view of a portion of the compressor assembly shown in Fig. 3 illustrating another modified form of my invention; and Fig. 6 is an exploded view of some of the elements shown in Fig. 5.

Referring now to Figs. 1 and 2, there is shown a hermetically sealed motor-driven refrigerant compressor unit 1. This unit includes a hollow generally-cylindrical shell 2 to which end plates 3 and 4 are welded or otherwise suitably bonded to form a closed casing. An electric motor 5 is arranged within one end of the shell 2. The stator 6 of the motor is held between annular rings 7 and 8, which are welded or otherwise suitably bonded to the shell 2. The rotor 9 of the motor is arranged within the stator 6. Power is supplied to the stator windings through leads 10 which pass through sealed insulating fittings 11 from the exterior of the casing.

A compressor 12 is arranged within the casing at the opposite end of the shell 2. The compres-

2

sor includes a frame 13 which is rigidly secured within the casing. The compressor further includes a reciprocating piston (not shown) driven through a connecting rod 14 from a shaft 15. The connecting rod is carried on an eccentric or crank, portion 16 of the shaft 15 so as to convert the rotary motion of the shaft to reciprocating motion of the piston.

The shaft is carried within a longitudinal bearing 17 formed in the frame 13, and the hub 18 of the rotor 9 is secured in any suitable manner, as by a pressed fit, to the shaft 15, so that motion of the rotor is transmitted directly to the shaft. The hub in its assembled position may be regarded as an integral part of the shaft and is so treated in references in the claims to the axial passage for receiving the adjustable element.

The frame 13 is formed to provide two axially spaced thrust bearings 19 and 20. The shaft 15 is provided with a shoulder 21 which is adapted to engage the thrust bearing 19, thus limiting the axial movement of the shaft in one direction. In order to limit the axial motion of the shaft in the opposite direction an annular member or ring 22 is slidably arranged on the shaft and is adapted to engage the thrust bearing 20. As can be seen from the drawing, the end play of the shaft is determined by the distance between the shoulder 21 and the ring 22 relative to the distance between the thrust bearings 19 and 20. In order to adjust the amount of such end play an arrangement for varying the position of the ring 22 is provided. This arrangement includes a pin or member 23, which extends through an opening 24 in the shaft, and an adjustable element 25, which is received within an axial passage in the shaft. The adjustable element 25 includes a rod 26 and a screw-threaded portion 27 having a recessed end 28 for receiving the rod. Although

the adjustable element 25 has been shown as including the two portions 26 and 27 to facilitate alignment, it will be apparent as this specification proceeds that the adjustable element could be formed, if desired, as a unitary structure. The exposed end of the threaded portion 27 of the adjustable element is provided with a slot 29 for engagement by a screw driver during the adjusting operation. From the drawing it can be seen that the ring 22 can be positioned closer to or farther away from the shoulder 21 as the adjustable element 25 is screwed inwardly or outwardly with respect to the shaft 15. This provides a simple arrangement for adjusting the amount of end play so that, despite any slight variations in the sizes of the various parts of the compressor

unit resulting from mass production manufacturing tolerances, the amount of end play can be adjusted to any desired minimum. A lock nut 38 is provided for locking the adjustable element in its adjusted position.

The various parts which make up the adjusting structure are shaped along their engaging surfaces so as to provide for self-alignment thereof. Thus the ring 22 is provided with two arcuate aligned grooves 31, and the adjacent surface 32 of the pin 23 is correspondingly curved. The pin 23 includes a flat surface 33 which is engaged by a flat end 34 of the rod 26. By the construction outlined above any variations such as having the thrust bearing surface 20 not exactly perpendicular to the axis of the shaft or having the adjustable element 25 somewhat out of line with the axis of the shaft are automatically compensated from an alignment standpoint by the arrangement of the elements themselves.

Referring now to Figs. 3 and 4, there is shown a modified form of my invention. I have shown the hub 18' of a rotor secured, as by a pressed fit, to the shaft 15. A portion of the frame 13 is also illustrated, including the thrust bearing 20.

In order to provide for adjustment of end play an annular member or ring 35, corresponding to the ring 22 shown in the previously described form, is slidably arranged on the shaft 15 and is adapted to engage the thrust bearing 20. In order to position the ring 35 an adjusting structure is provided. This structure includes a second annular member or ring 36, which is adapted to engage the ring 35, and an adjustable element 37, which engages a portion of the ring 36. The adjustable element 37 is positioned within an axial passage 38 within the hub 18' and is provided with threads 39 for threaded engagement with the hub 18'. It can be seen by reference to Fig. 3 that screwing the adjustable element 37 inwardly or outwardly results in a shifting of the ring 35 to the right or left to decrease or increase the end play, in the same manner as the adjustment described in connection with the form illustrated in Figs. 1 and 2. The adjustable element 37 is provided with a slot 40 for engagement by a screw driver in making adjustments, and a nut 41 is provided for locking the element in the adjusted position.

In order to provide for alignment of the parts the surface 42 of the ring 35 on the side adjacent the ring 36 is curved as shown in the drawing. Thus the ring 35 has its maximum thickness along one transverse axis and its minimum thickness along a transverse axis at right angles to the first mentioned axis. In order to further facilitate self-alignment the left-hand face of the ring 36 as viewed in Figure 3, that is the under surface of this ring as viewed in Figure 4, may also be curved, the curvature being indicated by the dotted line 36a in Figure 3. The curvature of the face of the ring 36 is arranged so that a transverse line extending through the portions of the maximum thickness of the ring 36 is displaced 90° from the transverse axis extending through the portions of maximum thickness of the ring 35. In order that the rings 35 and 36 rotate as a unit the ring 35 is provided with a pin 43 which is adapted to fit within a recess 44 formed in the ring 36. Similarly, the ring 36 includes a pin 45 adapted to fit within a recess 46 in the ring 35. The pins and recesses are arranged along the axis which includes the portions of maximum thickness of the ring 35. The ring 36 includes a pin 47 which

fits within a recess 48 in the hub 18', so that the ring 36 and hence the ring 35 rotate along with the rotor. Although the adjustable element 37 has been illustrated as a unitary structure, it will be apparent that, if desired, this element could be formed in two parts, similar to the adjustable element 25.

Referring now to Figs. 5 and 6, there is shown another modified form of my invention which includes an alternative arrangement for effecting self-alignment. The compressor assembly structure is the same as that illustrated in Fig. 3 and the same numerals have been applied to corresponding parts.

Referring first to Fig. 5, there is illustrated a portion of the frame 13. There is also shown the hub 18' of the rotor secured, as by a pressed fit, to the shaft 15. Between the thrust bearing 20 on the frame 13 and the hub 18' there are arranged two annular members or rings 49 and 49'. The adjustable element 37 is arranged to bear against the ring 49' and motion of the adjustable element is transmitted through the ring 49' to the ring 49 to vary the end play of the 25 shaft relative to the frame.

The ring 49 corresponds generally to the ring 35 shown in Fig. 3, but both faces of the ring 49 are flat whereas one face of the ring 35 is curved, as shown at 42, to facilitate self-alignment. In 30 order to provide for universal self-alignment, the ring 49' is provided with raised portions 50 and 51 on opposite faces of the ring, and these portions are arranged along axes spaced 90 degrees from each other. The raised portion 50 35 engages the adjacent face of the ring 49 and the raised portion 51 engages the hub 18'. By this construction the ring 49' may pivot about axes arranged at 90 degrees relative to each other so as to compensate for misalignment.

In order to prevent relative rotation between the rings 49 and 49', the ring 49' is provided with two openings 52 along the axis of the raised portion 50. Two pins 53 are provided on the ring 49 and are adapted to fit within the 45 openings 52 in the assembled position of the rings so as to prevent relative rotation of the rings. Similarly, the ring 49' is provided with an opening 54 along the axis of the raised portion 51, and a pin 5 provided in the hub 18' is adapted 50 to fit within the opening 54 to prevent relative rotation between the rotor and the ring 49'. The adjustable element 37 is arranged to engage the ring 49' along the axis of the raised portion 51 at a point 180 degrees from the opening 54.

While I have shown and described specific embodiments of my invention, I do not desire my invention to be limited to the particular constructions shown and described and I intend, by the appended claims, to cover all modifications 60 within the spirit and scope of my invention.

What I claim as new and desire to secure by Letters Patent of the United States is:

1. In a compressor or the like, a frame including a shaft bearing, a shaft journaled in 65 said bearing, a first thrust bearing formed on said frame, said shaft including a shoulder adapted to engage said first thrust bearing, a second thrust bearing formed on said frame and axially spaced from said first thrust bearing, a 70 first member arranged on said shaft and adapted to engage said second thrust bearing, said shaft having an axially extending passage therein, means for adjusting the end play of said shaft relative to said frame, said means including a 75 second member engaging said first member

and an adjustable element received in said passage for engaging said second member to vary the position of said first member, at least one of said members being curved with respect to a plane extending transversely of said shaft to facilitate self-alignment.

2. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, an annular member arranged on said shaft and adapted to engage said second thrust bearing, said shaft having an axially extending passage therein, means for adjusting the end play of said shaft relative to said frame, said means including a second member engaging said annular member, and an adjustable element received in said passage for engaging said second member to vary the position of said annular member, at least one of said members being curved with respect to a plane extending transversely of said shaft to facilitate self-alignment.

3. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, an annular member arranged on said shaft and adapted to engage said second thrust bearing, means for adjusting the end play of said shaft relative to said frame, said means including a pin extending transversely through said shaft and engaging said annular member, and an adjustable element for engaging said pin to vary the position of said annular member.

4. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, a first member arranged on said shaft and adapted to engage said second thrust bearing, said shaft having an axially extending passage therein, means for adjusting the end play of said shaft relative to said frame, said means including a second member engaging said first member, an adjustable element received within said passage for engaging said second member to vary the position of said first member, at least one of said members being curved with respect to a plane extending transversely of said shaft to facilitate self-alignment, and means for locking said adjustable member in its adjusted position.

5. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, said shaft having an axial passage therein, a first member arranged on said shaft and adapted to engage said second thrust bearing, means for adjusting the end play of said shaft relative to said frame, said means including a second member engaging said first member, the engaging surfaces of said members being curved with

respect to a plane extending transversely of said shaft to facilitate self-alignment, and an adjustable element extending through said passage and in threaded engagement therewith for engaging said second member to vary the position of said first member.

6. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, said shaft having an axial passage and a transverse passage therein, a first member arranged on said shaft and adapted to engage said second thrust bearing, means for adjusting the end play of said shaft relative to said frame, said means including a second member extending through said transverse passage and engaging said first member, and a threaded element arranged within said axial passage and engaging said second member to vary the position of said first member.

7. In a compressor or the like, a frame including a shaft bearing, a first thrust bearing formed on said frame, said shaft including a shoulder adapted to engage said first thrust bearing, a second thrust bearing formed on said frame and axially spaced from said first thrust bearing, said shaft having an axial passage and a transverse passage therein, a ring arranged on said shaft and adapted to engage said second thrust bearing, said ring having a transverse groove therein, means for adjusting the end play of said shaft relative to said frame, said means including a pin extending through said transverse passage in said shaft and having a rounded surface adapted to fit within said groove, said pin including a flat surface, and an adjustable element arranged in threaded engagement with said axial passage in said shaft for engaging the flat surface of said pin to vary the position of said ring.

8. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, two rings arranged on said shaft, one of said rings being adapted to engage said second thrust bearing and at least one of said rings being curved with respect to a plane extending transversely of said shaft to facilitate self-alignment of said rings, and an adjustable element for engaging one of said rings to vary the end play of said shaft relative to said frame.

9. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, two rings arranged on said shaft, one of said rings being adapted to engage said second thrust bearing, at least one of said rings having a curved face to facilitate self-alignment of said rings, at least one pin arranged between adjacent faces of said rings at the point of maximum thickness of said ring having said curved face to prevent relative rotation between said rings, and an adjustable element for engaging one of said

7 rings to vary the end play of said shaft relative to said frame.

10. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, two rings arranged on said shaft, one of said rings being adapted to engage said second thrust bearing, at least one of said rings having a curved surface to facilitate self-alignment of said rings, a pin extending between adjacent surfaces of said rings to prevent relative rotation of said rings, a second pin extending between one of said rings and said shaft to prevent relative rotation between said rings and said shaft, said shaft having a longitudinal passage therein, and an adjustable element extending through said passage and engaging said last-named one of said rings at a position substantially 180 degrees from said second pin for varying the end play of said shaft relative to said frame.

11. In a compressor or the like, a frame including a shaft bearing, a shaft journaled in said bearing, a first thrust bearing formed on said frame, said shaft including a shoulder adapted to engage said thrust bearing, a second thrust bearing formed on said frame and axially spaced from said first thrust bearing, two rings arranged on said shaft, one of said rings being adapted to engage said second thrust bearing, each of said rings having a curved surface to facilitate self-alignment, the axes of said curved surfaces of said rings being spaced 90 degrees from each other, the adjacent faces of said rings including a plurality of cooperating pins and recesses to prevent relative rotation between said rings, said shaft including a recess and a longitudinal passage, one of said rings including a pin adapted to engage said recess in said shaft for preventing relative rotation between said one of said rings and said shaft, an adjustable element extending through said longitudinal passage in said shaft in threaded engagement therewith and engaging said one of said rings at a position substantially 180 degrees from said last-mentioned pin to vary the end play between said shaft and said frame, and means for locking said adjustable element in its adjusted position.

12. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing,

8 a first ring arranged on said shaft and adapted to engage said second thrust bearing, a second ring arranged on said shaft and adapted to engage said first ring, said second ring being shaped to provide raised portions on opposite faces thereof arranged along axes spaced 90 degrees from each other to facilitate self-alignment, and an adjustable element for engaging said second ring at a point along one of said axes to vary the end play of said shaft relative to said frame.

13. In a compressor or the like, a frame including a shaft bearing, a shaft journaled in said bearing, a first thrust bearing formed on said frame, said shaft including a shoulder adapted to engage said first thrust bearing, a second thrust bearing formed on said frame and axially spaced from said first thrust bearing, a first ring arranged on said shaft and adapted to engage said second thrust bearing, a second ring arranged on said shaft and adapted to engage said first ring, said second ring being shaped to provide raised portions on opposite faces thereof arranged along axes spaced 90 degrees from each other to facilitate self-alignment, said second ring including an opening arranged at a point along one of said axes, said first ring including a pin adapted to fit within said opening to prevent relative rotation between said rings, said second ring including a second opening arranged at a point along the other of said axes of said second ring, said shaft including a pin adapted to engage said second opening for preventing relative rotation between said second ring and said shaft, and an adjustable element arranged in threaded engagement with said shaft and adapted to engage said second ring at a point along the same axis as said second opening for varying the end play of said shaft relative to said frame.
